FIG13

FIG. 4

FIG. 5

FIG. 1 is a front perspective view of an automobile embodying my novel design;

FIG. 2 is a rear perspective view thereof;

FIG. 3 is a left side elevational view thereof;

FIG. 4 is a front elevational view thereof;

FIG. 5 is a rear elevational view thereof;

FIG. 6 is a front perspective view of the automobile shown in FIG. 1 with the hard top removed;

FIG. 7 is a rear perspective view thereof;

FIG. 8 is a left side elevational view thereof;

FIG. 9 is a front elevational view thereof;

FIG. 10 is a rear elevational view thereof;

FIG. 11 is a front perspective view of an automobile showing a second embodiment of my novel design, the difference being in the replacement of the hard top by a convertible top;

FIG. 12 is a rear perspective view thereof;

FIG. 13 is a left side elevational view thereof;

FIG. 14 is a front elevational view thereof; and

FIG. 15 is a rear elevational view thereof.

I claim:

The ornamental design for an automobile, as shown.
